AXLE BOX

Application filed April 2, 1929. Serial No. 351,959.

The object of our invention is to make a substantial and comparatively light axle box. This object we attain by making the box from rolled, pressed or forged steel shapes assembled and welded together. An axle box in the manner which will be described herein can be readily manufactured at a low cost.

In the accompanying drawing:

Fig. 1 is a perspective view of our improved 10 axle box;

Fig. 2 is a sectional elevation on the line 2—2, Fig. 3; and

Fig. 3 is a sectional plan view on the line 3—3, Fig. 2.

15 The axle box shown in the drawing is of a shape to receive a roller-bearing of a standard type, but it will be understood that the box can be of any design desired without departing from the essential features of the 20 invention.

The body 10 of the box is made of two-half sections 12—12, shaped in the present instance to receive a roller-bearing shown by dotted lines in Fig. 2. The inner raceway of 25 this roller-bearing is secured to the axle and the outer raceway fits against a shoulder formed by an internal rib 13 of the box. In the present instance the outer end of the box is rounded as at 14 and the opening in the end 30 is closed by any suitable lid or cover.

The rear end of the box is open for the axle and its connected parts, and has a slight internal flange 15 and an external flange 16. A dust ring is secured to the rear of the box as 35 shown by dotted lines, Fig. 2.

The two sections 12—12 of the body of the box are made from a rolled strip of a cross-section similar to the cross-section of 40 the box and bent to form one-half of a cylinder. The two sections, when assembled as shown in Fig. 1, are welded together in any suitable manner.

The only finish necessary is a grinding on 45 the two abutting edges of the sections of the box, and the seat for the lid and for the dust ring.

In order to reinforce the body of the box and to provide pedestal guides for the box, 50 the two rings 17—17^a are formed as shown in

Fig. 1. These rings are cut from a rolled blank, punched and shaped as shown.

The front ring 17 in the present instance is shaped to fit a portion of the curved surface 14 of the body as shown in Fig. 3, and has a 55 pedestal way 18 at each side of the shape shown in the drawing. The rear ring 17^a fits the rear portion of the body and has a pedestal way 18^a at each side. When the rings 17—17^a are forced onto the body of the 60 box, the two sections 12—12 are drawn close together and the entire structure welded in any suitable manner.

Located between the two ring sections 17—17^a is an equalizer seat 20, made of 65 pressed sheet metal and provided with a rib 19 which extends into a notch in an equalizing beam of any suitable type. On each side of the seat 20, and preferably located between the seat and the rings, are chafing plates 21. 70 Between the inner ring 17^a and the flange 16 are spacers 22. The seat 20, chafing plates 21 and spacers 22 are welded to the structure.

Where the upper section of the body differs materially from the lower section, then 75 the sections can be made from rolled stock differing in form.

While the body of the box as described above is made of two sections formed from 80 rolled strips bent into shape, the sections may be made from plates bent or forged into the shape desired, and the rings may be made in the same manner.

An axle box of the type described can be 85 cheaply and accurately manufactured and is lighter and stronger than the ordinary cast axle box. The box illustrated is particularly adapted as a roller bearing axle box for heavy rolling stock.

We claim:

1. An axle box in which the body is made of two sections, and two rings which encircle the sections and form the pedestal guides.

2. An axle box in which the body of the 95 box is made of two semi-cylindrical wrought metal sections welded together.

3. An axle box in which the body of the box is made of two semi-cylindrical wrought metal sections, and wrought metal rings en- 100

circling the body, the whole being welded together.

4. An axle box in which the body of the box is made in two sections, with two rings 5 encircling the body and spaced apart, each ring having vertical ribs forming pedestal guides, the whole being welded together.

5. An axle box in which the body of the box is made in two sections, with two rings 10 encircling the body and spaced apart, each ring having vertical ribs forming pedestal guides, and an equalizer plate on the upper portion of the box between the rings, the whole being welded together.

15 6. An axle box in which the body of the box is made in two sections, with two rings encircling the body and spaced apart, each ring having vertical ribs forming pedestal guides, and an equalizer plate on the upper 20 portion of the box between the rings, and a chafing plate between the equalizer plate and each ring, the whole being welded together.

7. An axle box having a wrought metal body portion cylindrical in form; and rings 25 encircling the body portion and secured thereto.

8. An axle box made of wrought metal and having a cylindrical body portion; and reinforcing rings which encircle the body portion, said rings being spaced apart and forming pedestal guides.

9. An axle box of wrought metal having a cylindrical body portion shaped on the inside to receive a roller-bearing; two wrought 35 metal rings spaced apart; and vertical ribs forming pedestal guides, said ribs being welded to the body portion.
